UNITED STATES PATENT OFFICE.

HORATIO G. GILLMOR, OF WASHINGTON, DISTRICT OF COLUMBIA.

ANTICREEPER.

1,204,659.

Specification of Letters Patent. Patented Nov. 14, 1916.

Application filed April 14, 1915. Serial No. 21,434.

To all whom it may concern:

Be it known that I, HORATIO G. GILLMOR, of Washington, in the District of Columbia, have invented a new and useful Improvement in Anticreepers, of which the following is a specification, accompanied by drawings.

This invention relates to devices known as rail anticreepers, rail anchors or rail stays and one of its objects is to form a simple device which will prevent longitudinal movement of the rails of railways.

Other objects of the invention are to provide means for securing the device upon the rails in such manner that it cannot be loosened by vibration or reverse movement of the rail and to provide a device which shall be effective against movements in either direction.

20 To the accomplishment of these objects and such others as may hereinafter appear, as will be readily understood by those skilled in the art, the invention comprises an anti-creeper, embodying the features of construction, the combination of elements and arrangement of parts having the general mode of operation as hereinafter described and claimed.

The preferred embodiment of the invention is shown in the accompanying drawings, in which:—

Figures 1 and 2 are, respectively, a plan view and a transverse sectional view of the device in operative position. Figs. 3 and 4 are, respectively, a plan view and a transverse sectional view showing positions of the device while being placed upon the rail. Fig. 5 is a view of the device detached from the rail.

40 Similar letters refer to similar parts throughout the several views.

A represents the rail. B is the anti-creeper which comprises a flat bar recessed on one edge, as shown at C to fit the bottom of the rail flange and present shoulders or faces D and E which engage the two edges of the base flange of the rail A. Beyond the shoulders C and D the bar is turned back in the form of partial loops F and G and the ends of the bar are each formed with jaws H and I arranged to engage the base flange of the rail at opposite sides of the rail with the arms K and L above and

the broad flat portions M and N below the rail base. P and O are two ties.

55 The device is placed in position on the rail by placing the body B transverse and inclined to the rail with the base flange at one side entered in the jaw H and the shoulder E and the arm L of the other end of B clearing the other edge of the rail base as illustrated in Fig. 3. The whole is then moved angularly in relation to the rail and at the same time the end having the jaw I is sprung upwardly so that the jaw I will 60 engage the rail base at the side of the rail. The parts are then in the position illustrated in Fig. 4 and the body B is under torsion. The shoulder D is, in this position, 65 underneath the rail base. The opposite ends of B are then driven in opposite directions toward the ties O and P until a position substantially transverse to the rail base is reached by B and when this position is 70 reached the shoulder D springs up into engagement with the edge of the rail base as shown in Figs. 1 and 2. In this position the rail base is gripped at opposite sides of the rail and at opposite sides of the transverse bar B by the jaws H and I and the 75 opposite edges of the rail base are engaged by the shoulders D and E.

The grip of the jaws H and I upon the rail insures that the device will move with the rail until one or the other of the portions M or N come into contact with the tie. In the drawings it is assumed that the rail normally tends to move in the direction of the arrow in Fig. 1 and this direction will be referred to as forward. After the 80 rail moving forwardly has brought M into engagement with the tie O, the contact of M with the tie O will prevent further movement of M forwardly, and, if the grip of the device on the rail is not then sufficient 85 to hold the rail against the forces operating to cause it to move forwardly, further movement of the rail in the forward direction will carry the jaw I and the shoulder E forward with the rail and will cause the body 90 B to assume a new position at an angle to its first position. The effect of this will be to increase the pressure of the shoulders D and E upon the rail edges and tighten the 95 grip of the device upon the rail until the 100 grip of the device becomes sufficient to hold

the rail against further movement in this direction.

Should the rail A, on account of change in temperature or for any other reason move in the reverse or backward direction, it will carry with it the device B and the portion M will be carried out of contact with the rail if this movement continues. Should this occur, the engagement of the jaws H and I with the rail bases and the torsion of B will prevent vibration from loosening or disengaging the device from the rail. Moreover, should this rearward or backward movement of the rail continue, the portion N will come into contact with the tie P and when this takes place the device will be subject to the same automatic tightening action upon the rail until the grip of the device upon the rail is sufficient to resist this rearward movement of the rail. It will readily be understood that if the ties O and P were so spaced that the portions M and N of the device were in contact at the same time with the ties O and P, respectively, the rail would be held against movement in either direction except for such small movement as might be necessary to bring about such tightening of the grip of the device in passing from movement in one direction to movement in the other direction.

Obviously some features of the invention may be used without others and the invention may be embodied in widely varying forms within the scope of the artisan.

35 Therefore, without limiting the invention to the construction shown and described or enumerating equivalents, I claim and desire to secure by Letters Patent:—

1. A rail stay, comprising a cross bar 40 recessed to receive the rail base flange and engage the opposite vertical edges thereof, held in engagement with said rail base by the upward components of opposing torsional forces.

45 2. A rail anchor, comprising a cross bar having two shoulders adapted to engage edges of a rail base flange at opposite sides of the rail, said bar engaging and exerting upward pressure upon the bottom of the rail base flange at opposite sides of the rail in tending to assume a position from which it was sprung and means whereby one end of said bar is given a fixed position in the roadbed as against the tendency of the rail 55 to creep.

3. An anticreeper comprising a transversely disposed bar having a recess arranged to engage the bottom and opposite edges of the base flange of a rail and arms 60 at opposite sides of said bar adapted to engage the upper surface of the rail base at opposite sides of the rail and means engaging a tie for holding one end of said bar in spaced relation to said tie.

4. A device for preventing the creeping 65 of rails comprising a flat transverse bar having a recess at one edge engaging the bottom and opposite edges of the rail base and the ends thereof turned back at opposite sides of said bar and provided with jaws adapted to engage the rail base at opposite sides of the rail.

5. A rail stay comprising a flat bar, transverse to the rail, having one edge thereof cut out to engage the bottom and the opposite edges of the rail base and the ends thereof turned back to form arms adapted to engage the rail base at opposite sides of the rail and maintain torsional stresses in said bar.

6. A rail anchor comprising a cross bar having at one end a tie engaging portion, an integral rail base engaging jaw and an integral rail base edge engaging shoulder and at the other end an integral rail base edge engaging shoulder and an integral rail base engaging jaw, said rail base engaging jaws lying at opposite sides of said cross bar.

7. An anticreeper, comprising a transversely disposed bar constructed to engage the bottom and opposite vertical edges of the rail base and having two jaws yieldably connected to said bar arranged to engage the rail base one at one side of the rail forward of said bar and the other at the other side of the rail back of said bar.

8. A rail anchor comprising a cross bar provided with a rail base engaging jaw and a rail base engaging face at one end and a 100 reversely disposed base engaging jaw and a rail base edge engaging face at the other end thereof so arranged that when said jaws are applied to the rail base at opposite sides of the rail said rail base edge engaging faces 105 may be sprung into engagement with the edges of the rail base flange.

9. A rail stay comprising a cross bar extending beneath the rail foot flange having a surface adapted to engage the bottom of 110 said flange and two shoulders adapted to engage opposite edges of said foot flange, means at one end of said bar for engaging one side of said foot flange at one side of said bar, means for engaging the other side 115 of said flange at the other side of said bar, said flange bottom engaging surface being pressed against the flange bottom by opposing torsional stresses applied at the ends of said bar, and means for engaging a tie 120 projecting from one end of said bar.

10. An anticreeper comprising a bar for transverse application beneath the rail base flange having a recess adapted to engage the opposite edges and the bottom of said rail 125 base flange, means on one end of said bar for engaging the upper surface of the rail base flange at one side of the rail, means

- on the other end of said bar for engaging the upper surface of the base flange at the other side of the rail, tie-engaging means projecting from one end of said bar from 5 one side thereof, and tie-engaging means projecting from the other end of said bar at the opposite side thereof. 40
11. An anticreeper comprising a transverse bar having rail edge gripping shoulders adapted to increase their grip upon the rail upon a tendency of said bar to skew and two arms at opposite sides of said bar adapted to engage upper surfaces of the rail base flange at opposite sides of the rail 10 45
- 15 to hold said bar in operative engagement with the rail and means engaging a tie and holding one end of said bar in spaced relation to said tie. 50
12. A rail stay comprising a cross bar 20 having a recess adapted to receive the rail base and grip the edges thereof between two faces the grip of said faces tending to increase with angular movement of said bar in relation to said rail and arms, symmetrically disposed in relation to said bar, having jaws adapted to grip the rail base at opposite sides of the rail for retaining the rail base in engagement with the recess in 25 said bar. 55
- 30 13. A reversible anticreeper comprising a cross bar having shoulders adapted to engage and grip opposite edges of a rail base flange and arms symmetrically disposed in relation to said bar each adapted to engage 35 the base flange above the rail base and the tie below the rail base in such manner that movement of the rail in relation to the ties will produce angular movement of said bar 60 65
14. A device for limiting the longitudinal movement of rails in either direction comprising a transverse bar having oppositely disposed faces adapted to engage and grip the rail base edges, means forward of said bar at one end thereof for engaging the rail base above and the tie face below the rail and means in rear of said bar and at the other end thereof for engaging at the other side of the rail the upper surface of the rail 60 65 base above the rail and the face of a tie below the rail. 70
15. A rail anchor comprising an S-shaped bar arranged for transverse application to the rail base having at its ends rail base engaging apertures adapted to engage a rail base at opposite sides of the rail and two shoulders adapted to engage and grip opposite edges of the rail base. 75
16. A one piece anticreeper having shoulders adapted to engage opposite vertical edges of the rail base and means for preventing forward movement of the rail in relation to a cross tie, said anticreeper being held to the rail by the upward component of opposing torsional couples. 80
17. A rail stay comprising a substantially S-shaped cross bar having end tie engaging portions adapted to engage the faces of two adjacent ties and shoulders engaging and gripping opposite edges of a rail base. 85 90
